FIG. 5.

UNITED STATES PATENT OFFICE.

THOMAS O'DONNELL, OF IRONWOOD, MICHIGAN.

LAMP-SOCKET.

1,163,446.

Specification of Letters Patent. Patented Dec. 7, 1915.

Application filed May 24, 1915. Serial No. 30,219.

To all whom it may concern:

Be it known that I, THOMAS O'DONNELL, a citizen of the United States, residing at Ironwood, in the county of Gogebic and State of Michigan, have invented certain new and useful Improvements in Lamp-Sockets, of which the following is a specification.

My invention relates to improvements in electrical cluster lamp sockets. 10 An important object of the invention is to provide apparatus of the above mentioned character, formed of few and simple parts which may be readily separated and assembled.

15 A further object of the invention is to provide means of the above mentioned character, which are attractive and neat in appearance.

Other objects and advantages of the invention will be apparent during the course 20 of the following description.

In the accompanying drawings forming a part of this specification and in which like numerals are employed to designate like 25 parts throughout the same, Figure 1 is a central longitudinal sectional view through a socket embodying my invention, Fig. 2 is a horizontal sectional view taken on line 2—2 of Fig. 1, Fig. 3 is a similar view taken on line 3—3 of Fig. 1, Fig. 4 is a similar view taken on line 4—4 of Fig. 1, and Fig. 5 is a perspective view of conducting elements.

In the drawings, wherein for the purpose of illustration is shown a preferred embodiment of my invention, the numeral 10 designates a metallic casing, having an upper detachable cap 11' provided with an opening 11. The lower end of the casing 10 is flared and decreases in diameter downwardly and 40 has a cap 12, detachably connected therewith by any suitable means.

Arranged within the casing 10 is a main insulating member or support 13, formed of wood, fiber, porcelain, or any other suitable 45 material. Arranged upon the top of the main insulating support 13 is an upper auxiliary insulating support 14, disposed in the cap 11'. The upper end of the main insulating support 13 and the lower end of the auxiliary insulating support 14 are provided 50 with a recess or chamber 15, within which is arranged a pivoted contact switch element 16, adapted to engage and disengage a stationary contact switch element or spring contact 17. The movable contact element 16 is rigidly mounted upon a metallic rod or rock-

shaft 18, journaled through the ends of a metallic bracket 19, arranged in the lower portion of the chamber 15. The rock-shaft 18 extends through openings 20 and projects exteriorly of the casing 10, and carries an insulating key or knob 21, as shown. The spring contact 17 is secured to the upper auxiliary insulating support 14 by a bolt 22 or the like. 65

The auxiliary insulating support 14 is held fast to the upper end of the main insulating support 13 by a screw 23 or the like, having electrical contact with the contact element 17, as shown at 24. The main insulating support 13 is provided upon one side with a recess or chamber 25 within which are arranged stationary contacts 26 and 27. The stationary contact 27 has a screw-threaded opening for receiving the lower end of the screw 23. The contact 27 has a binding post 28 for engagement with a wire 29 and the contact 26 has a binding post 30 for engagement with a wire 31. The wires 29 and 31 have connection with the opposite pole of 80 the source of current and are arranged in a groove 32, and pass out through the opening 11.

Arranged beneath the main insulating support 13 is a lower auxiliary insulating support 33, held in place by a bolt 34, passing centrally therethrough and having screw-threaded engagement with the bracket 19. The upper end of the auxiliary support 33 is provided with an annular groove 35, 90 receiving an insulating ring 36 and a metallic conducting element or ring 37. The metallic ring 37 has screw-threaded engagement with a bolt 38, engaging the contact element 26, as shown. Arranged beneath the annular groove 35 is a central recess 39, within which is arranged a metallic conducting element 40, preferably in the form of a spider, which is apertured for receiving the bolt 34 and has electrical contact therewith. 100

The cap 12 is provided with two or more sleeves 41, (only one being shown), holding insulating rings 42. Arranged within the insulating rings 42 is a screw-threaded metallic sleeve 43, electrically connected by 105 means of bolt or bolts 44 with the conducting ring 37. This metallic sleeve 43 is adapted for engagement with a screw-threaded socket 45 of an electric lamp 46. The opposite terminal 47 of this electric lamp contacts 110 with the head of a bolt 48, passing through the insulating support 32 and having electrici-

cal contact with the conducting element 40, as shown.

The operation of the apparatus is as follows: When the switch 21 is turned whereby contact 16 has electrical contact with the contact element 17, a circuit is closed to cause the lamp or lamps to glow. In this closed circuit current flows from one pole of the source of current through wire 29, contact 27, bolt 23, contact 17, contact element 16, bracket 19, bolt 34, conducting element 40, bolt 48, terminal 47, the filament of the lamp, terminal 45, sleeve 43, bolt 44, ring 37, bolt 38, contact 26, and through wire 31 back to the opposite pole of the source of current.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In apparatus of the character described, the combination with a main insulating support provided in its upper end with a chamber, of a bracket arranged in the chamber, a rock-shaft journaled through the bracket, a contact element carried by the rock-shaft, a co-acting contact element arranged in the chamber near the first named contact element and secured to the insulating support, means for connecting one pole of a source of current with the co-acting contact element, an auxiliary insulating support secured to the opposite end of the main insulating support, a plurality of conducting elements arranged between the main insulating support and the auxiliary insulating support and insulated from each other, a bolt connecting the bracket with one conducting element, means connecting the other conducting element with the opposite pole of the source of current, and contact elements carried by the auxiliary insulating support and electrically connected with the conducting elements and adapted for contacting with the terminals of an electric lamp, substantially as described.

2. In apparatus of the character described, the combination with a main insulating support provided in its upper end with a chamber, of a bearing arranged in the chamber, a rock-shaft journaled through the bearing, a contact element carried by the rock-shaft, a relatively stationary contact element arranged within the chamber near the first named contact element, means for connecting the relatively stationary contact element

with one pole of a source of current, an auxiliary insulating support arranged upon the lower end of the main insulating support, a bolt passing longitudinally through the auxiliary insulating support and the main insulating support to secure them together and engaging the bearing, a plurality of conducting elements arranged between the main insulating support and the auxiliary insulating support with one conducting element engaging the bolt, means connecting the other conducting element with the opposite pole of the source of current, and contact elements having electrical connection with the conducting elements and carried by the auxiliary insulating support for contacting with the terminals of an electric lamp, substantially as described.

3. In apparatus of the character described, a main insulating support, an auxiliary insulating support disposed at one end of the main insulating support, a bolt passing longitudinally through the insulating supports to bind them together, a plurality of conducting members arranged between the insulating support and insulated from each other with one conducting member engaging the bolt, means connecting the bolt with one pole of the source of current, means connecting the opposite conducting member with one pole of the source of current, and contact elements carried by the auxiliary insulating support and electrically connected with the conducting elements and adapted to contact with the terminals of an electric bulb.

4. In apparatus of the character described, an insulating support provided upon one side with a chamber, switch means carried by one end of the insulating support and embodying a plurality of contact elements, a binding post arranged within the chamber and having electrical connection with one contact element, a plurality of conducting members carried by the other end of the insulating support, a second binding post arranged within the chamber and electrically connected with one conducting element, means electrically connecting the other conducting element with the other contact element, and contacts carried by the insulating support and electrically connected with the conducting elements and adapted to contact with the terminals of an electric lamp, substantially as described.

In testimony whereof I affix my signature in presence of two witnesses.

THOMAS O'DONNELL.
